SPLASH GUARD

Walter C. Jackson, Rahway, N. J., assignor to
Tingley-Reliance Rubber Corporation, a corpora-
tion of New Jersey

Application October 8, 1935, Serial No. 44,005

19 Claims. (Cl. 208—141)

This invention relates to bicycle or motorcycle fender splash guards of the type adapted to be attached to a stand holding clip that depends from the lower end of the fender at the rear. 5 More specifically, the present improvements deal with devices whereby the splash guard may be readily attached to the clip.

In accordance with the present invention, there is provided a flexible apron, preferably made of 10 vulcanized rubber, formed in its upper central portion with a pair of spaced lugs, likewise made of rubber, permanently vulcanized into the apron. Bridging the lugs, but movable with respect thereto, is a member having a base portion arranged to fit between the lugs and which in its outer portion is formed with a pair of spaced ears, the end outer surfaces of which flare outwardly from the lugs and which cooperate with the lugs in such manner that, as the bridge 15 member is drawn inwardly toward the apron, a wedging action occurs that acts to force the ears inwardly toward each other. In attaching the guard to the stand clip, the ears are located one at each side of the clip, and then pressed 20 against the latter, causing the ears to be sprung apart until the clip seats in a pair of opposed recesses formed at the base of the ears just above the body portion of the bridge member, whereupon the ears will spring back into place 25 and firmly grip the clip. Thereafter, the bridge member is moved relatively to the lugs in toward the apron, the ears thus being forced inwardly in the manner previously mentioned, to grip the clip more tightly and hold the splash 30 guard firmly in position.

Rigidity is lent to the lugs by a U-shaped metal member, the base portion of which is vulcanized 35 into the apron and the flange portions of which project into the lugs. Resiliency, in addition to that which is inherent in the material of which the bridge member is made, is given to the ears by a metallic clip having a base portion vulcanized 40 into the base portion of the bridge member and two arm portions flaring outwardly from the base portion and extending into the ears.

Of course, means are provided for drawing the bridge member in toward the apron of the guard, so as to secure the additional gripping action 45 previously alluded to. In effect, what the invention provides is a splash guard which may be readily applied to a fender, without in any way altering the parts of the machine with which it is associated, and with a minimum of effort and skill.

Referring to the drawing:

Fig. 1 is a view in elevation of a splash guard embodying the present improvements and which is shown secured to a bicycle stand holding clip depending from the rear fender of a bicycle; 5

Fig. 2 is a horizontal sectional view through the splash guard retaining means before it has been applied to the stand holding clip;

Fig. 3 is a view similar to Fig. 2, but showing 10 the guard attached to the clip;

Fig. 4 is an exploded view in perspective of 15 the guard and its retaining means, a portion only of the apron however being shown;

Figs. 5 and 6 are perspective views of the lug 20 and the bridge member reinforcing means, respectively.

As shown in Fig. 1, the fender splash guard A in service is attached to a bicycle stand retaining clip B which, as is the custom, is permanently secured to the rear fender C of the 25 bicycle. The clip B is mounted on the inside of the fender, i. e., the side adjacent the wheel, either by riveting or by a bolt and slot connection C¹ and extends below the lower edge of the fender where it is bent, as at B², to receive 30 the stand.

The splash guard A at its upper end fits beneath the fender C and is snapped on to the stand holding clip B from the rear of the latter, so that when the guard is in place, it rests behind 35 the clip B, i. e., between it and the wheel.

Preferably the fender guard A includes a flexible vulcanized rubber apron A¹ with the holding means by which it is secured to the clip B located in the upper central portion thereof. 40 The holding means in part includes a pair of spaced lugs A² projecting from the apron on the side facing the clip and which too, are made of rubber vulcanized to the apron. In order to give the lugs rigidity for a purpose which will hereinafter be described, there is provided a U-shaped metal clip A³ having a base portion a embedded in the apron and two flange portions a¹ projecting from the base portion a at the ends 45 thereof and which extend into the lugs A² (see Figs. 2 and 5).

The holding means further includes a vulcanized rubber member D bridging the space between the lugs and which is formed with a base portion D¹ positioned between the lugs A², and a pair of spaced ears D² projecting from the base portion and adapted to be sprung, one on each side of the clip B. The ears, in their outer or end faces, where the bridge member 55

engages the lugs A², flare outwardly from the base portion D¹, whereas in their inner faces, said ears are formed with a pair of opposed recesses d immediately above the base portion and 5 in which the stand holding clip B is adapted to seat.

The bridge member D is reinforced by a metal clip D³ which, as shown in Figs. 2 and 6, includes a flat base portion d¹ formed with a square hole 10 d² centrally located therein, two lateral flanges d³ to give the base portion rigidity and two end portions d⁴ extending from the base portion at an angle substantially the same as that of the flaring end surfaces of the ears, and which at 15 their ends curve inwardly one toward the other. It may be noted here, that the end portions d⁴ are reduced in width, intermediate their ends in order to allow for the separation of the ears as the latter are sprung into place on the stand 20 holding clip B, and also to permit the ears to yield at this point as the bridge member is pulled in toward the apron.

The bridge member D is held in place between the lugs by a bolt E formed with a flat head E¹ 25 which seats in a recess D⁴ provided in the bridge member in the surface thereof resting against the stand holding clip B when the latter is in place, and which bears against the outer surface of the metal reinforcing piece D. The bolt, for 30 a short portion just beneath its head, is formed with a square shank that fits the square hole in the reinforcing clip, thus preventing turning of the bolt with respect to said clip and extends through the apron A¹ and incidentally the metal 35 reinforcing member A³ therein, which is provided with a hole a² for the purpose, and is held in place by a washer E² and a nut E³ threaded on the end of said bolt.

In applying the guard to the stand holding 40 clip, the nut E³ is unscrewed slightly, allowing the bridge member D to be moved relatively to the lugs A² for a short distance away from the apron to the position shown in Fig. 2, wherein the ears D² will be free from the confining influence of the lugs A². The ears D², due to the 45 narrow width of the end sections of the clip D³ now may be separated sufficiently to permit the bridge member to be sprung on the stand holding clip B, the latter when in place seating against 50 the base portion of the bridge member and in the recesses d formed in the ears thereof. Thereafter, the bridge member is moved relatively to the lugs in toward the apron A¹ by screwing the 55 nut E³ up on the bolt E and, as this occurs, the ears D² will be pressed tightly against the clip B by virtue of the wedging action between the outer flaring surfaces of the ears and the inner edges of the lugs which are in contact therewith. This pressing action of the ears against the stand 60 holding clip is permitted due to the fact that the lugs A² are relatively rigid, whereas the ears are more flexible, since, as previously stated, the end portions of the clip reinforcing means are somewhat narrower in width than the remaining 65 portions.

As an additional precaution against inadvertent removal of the guard from the stand holding clip, it will be noted that when the ears have 70 been pressed in tightly against the clip, the turned-in ends of the reinforcing piece in the bridge member actually overlap the edges of the stand holding clip, so that even if it were possible for such clip to pull through the rubber, the metal piece D³ would act as a positive stop, preventing the guard from being removed.

In the accompanying drawing the invention has been shown merely by way of example and in preferred form, and obviously many variations and modifications may be made therein which will still be comprised within its spirit. For instance, it is not absolutely necessary for the fender to be equipped with a stand holding clip, since any suitable metal strip depending therefrom would serve as an equivalent means to which the splash guard could be secured, and where stand holding clip has been employed in the claims, such other equivalent means are intended to be included thereby. Then, too, although it is preferred that the holding devices be made of rubber with the metal reinforcement, they very readily could be made entirely of either rubber or metal, or any other suitable material for that matter, which will permit functioning of the parts as herein intended. It is to be understood, therefore, that the invention is not limited to any specific form or embodiment, except insofar as such limitations are specified in the appended claims.

Having thus described my invention, what I claim is:

1. A fender splash guard, adapted to be secured to a stand holding clip depending from the fender and including, in combination, a flexible apron and means for securing the apron to the clip, said means including devices associated with the apron and adapted to snap into engagement with the lateral edges of the clip.

2. A fender splash guard, adapted to be secured to a stand holding clip depending from the fender and including, in combination, a flexible apron and means for securing the apron to the clip, said means including devices associated with the apron and adapted to snap into engagement with the lateral edges of the clip, and means for augmenting the gripping action of said devices.

3. A fender splash guard, adapted to be secured to a stand holding clip depending from the fender and including, in combination, a flexible apron and means for securing the apron to the clip, said means including a pair of spaced lugs protruding from the upper central portion of the apron, a gripping device associated with the lugs and adapted to snap into engagement with the clip, and means for moving the gripping device relative to the lugs in a manner to augment the gripping engagement of said device and clip.

4. A combination according to claim 3, wherein in the apron and the gripping device are formed of vulcanized rubber.

5. A combination according to claim 3, wherein in the apron and the lugs therein referred to are formed of vulcanized rubber and wherein the lugs are provided with metallic reinforcing means.

6. A combination according to claim 3, wherein in the apron and the lugs therein referred to are formed of vulcanized rubber and wherein the lugs are reinforced by a metallic U-shaped clip, having its body portion embedded in the apron and its flange portions extending into and embedded in the lugs.

7. A combination according to claim 3, wherein in the gripping device therein referred to is formed of vulcanized rubber reinforced with a resilient metal member.

8. A fender splash guard, adapted to be secured to a stand holding clip depending from the fender and including, in combination, a flexible apron and means secured to one face of the apron cen-

trally of its upper portion and presenting a pair of spaced ears adapted to be moved apart as the clip is inserted between them and to return to grip the clip at its edges.

5 9. A fender splash guard, adapted to be secured to a stand holding clip depending from the fender, and including, in combination, a flexible apron and means secured to one face of the apron centrally of its upper portion and presenting a pair 10 of spaced ears of resilient material adapted to be sprung apart as the clip is inserted between them and to return to grip the clip at its edges.

10 10. A fender splash guard, adapted to be secured to a stand holding clip depending from the fender, and including, in combination, a flexible apron and means secured to one face of the apron centrally of its upper portion and presenting a pair of ears spaced apart in a horizontal direction when the guard is in service and consisting 15 at least partly of vulcanized rubber, said ears being adapted to be sprung outwardly as the clip is inserted between them and to return to grip the clip at its lateral edges.

20 11. A fender splash guard, adapted to be secured to a stand holding clip depending from the fender, and including, in combination, a flexible apron and means secured to one face of the apron centrally of its upper portion and presenting a pair of ears spaced apart in a horizontal direction 25 when the guard is in service and adapted to be moved outwardly as the clip is inserted between them and to return to grip the clip at its lateral edges, said means including a metal reinforcing member.

30 12. A fender splash guard, adapted to be secured to a stand holding clip depending from the fender, and including, in combination, a flexible apron and means secured to one face of the apron centrally of its upper portion and presenting a pair of ears spaced apart in a horizontal direction 35 when the guard is in service and adapted to be moved outwardly as the clip is inserted between them and to return to grip the clip at its lateral edges, said means comprising a rubber element 40 with a metal member embedded therein.

45 13. A fender splash guard, adapted to be secured to a stand holding clip depending from the fender, and including, in combination, a flexible apron, means secured to one face of the apron centrally of its upper portion and presenting a pair of spaced ears adapted to engage the clip at its lateral edges, and means for pressing the ears tightly against the clip.

50 14. A fender splash guard, adapted to be secured to a stand holding clip depending from the fender, and including, in combination, a flexible apron, means secured to one face of the apron centrally of its upper portion for attaching the apron to the clip, said means including a pair 55 of spaced lugs protruding from the apron, a member arranged between the lugs and presenting a pair of spaced ears adapted to engage the clip at its lateral edges, said lugs and said member having engaging surfaces so shaped that relative movement therebetween in one direction will act

to press said ears against the clip, and means for effecting such relative movement.

15. A fender splash guard, adapted to be secured to a stand holding clip depending from the fender, and including, in combination, a flexible 5 apron, means secured to one face of the apron centrally of its upper portion for attaching the apron to the clip, said means including a pair of spaced lugs protruding from the apron, a member arranged between the lugs and presenting a 10 pair of spaced ears adapted to engage the clip at its lateral edges, said member being formed at its ends with a pair of oppositely inclined surfaces engageable with the lugs and adapted upon relative movement in one direction between said lugs 15 and said member to press the ears tightly against the clip, and means for effecting such relative movement.

16. A fender splash guard, adapted to be secured to a stand holding clip depending from the 20 fender, and including, in combination, a flexible apron, means secured to one face of the apron centrally of its upper portion for attaching the apron to the clip, said means including a pair of spaced lugs protruding from the apron, a member 25 arranged between the lugs and presenting a pair of spaced ears formed with opposed recesses to receive the clip, said member being movable relatively to the lugs and so shaped that relative movement in one direction will act to press the 30 ears tightly against the clip, and means for effecting such relative movement of the parts.

17. A fender splash guard adapted to be secured to a stand holding clip depending from the fender, including, in combination, a flexible vul- 35 canized rubber apron and means for securing the apron to the clip, said means including a pair of spaced rubber lugs presenting opposed parallel faces vulcanized into the apron, a vulcanized rubber member bridging the space between the 40 lugs and formed with a base portion entering between the lugs and ears projecting from the base portion, the outer ends of said member adjacent the lugs being provided with surfaces flaring outwardly beyond the inner faces of the lugs, said 45 ears in their inner portions being formed with opposed recesses immediately above the base portion to receive the clip, and a bolt passing through the base of said member and through the apron, whereby as the bolt nut is screwed up, the bridge 50 member will be drawn toward the apron, the lugs acting on the flaring portions of the ears to effect a movement of the latter toward each other more tightly to grip the clip.

18. A combination according to claim 17, 55 wherein the bridge member is reinforced with metal, and wherein the outer portion thereof adapted to bear against the clip is recessed to receive the bolt head which is adapted to seat on the metal reinforcing member.

19. A combination according to claim 17, 60 wherein the bridge member is reinforced with a metallic strip having hook portions, adapted when the ears are pressed inwardly to overlap the clip member.

65 WALTER C. JACKSON.
